W. H. BAKER.

CALENDAR.

APPLICATION FILED JULY 1, 1922.

1,436,140.

Patented Nov. 21, 1922.

UNITED STATES PATENT OFFICE.

WILLIAM H. BAKER, OF NEWTON, KANSAS.

CALENDAR.

Application filed July 1, 1922. Serial No. 572,273.

To all whom it may concern:

Be it known that I, WILLIAM H. BAKER, a citizen of the United States, and a resident of Newton, in the county of Harvey and 5 State of Kansas, have invented a new and useful Improvement in Calendars, of which the following is a full, clear, and exact description.

My invention relates to improvements in 10 calendars, and it consists in the combinations, constructions, and arrangements herein described and claimed.

An object of my invention is to provide 15 an improvement over that form of the device shown in my prior application for patent on calendar, Serial No. 545,219, filed March 20, 1922. In said prior application there was disclosed a calendar composed of three discs, these discs having years, months, and days 20 imprinted thereon, and being operated from the rear side of the calendar. The construction of the present device is primarily designed to permit the discs to be actuated from the front side of the calendar.

25 A further object of my invention is to provide a device of the character described which has novel means for ascertaining the required calendar to be used.

30 A further object of my invention is to provide a device of the type described which is relatively simple in construction, and which may be used for a number of years.

Other objects and advantages will appear 35 in the following specification, and the novel features of the invention will be particularly pointed out in the appended claims.

My invention is illustrated in the accompanying drawings, forming part of this application, in which—

40 Figure 1 is a front elevation of the device, Figure 2 is an enlarged section along the line 2—2 of Figure 1,

Figure 3 is an enlarged section along the line 3—3 of Figure 1, and

45 Figure 4 is a section along the line 4—4 of Figure 1.

In carrying out my invention, I provide a metal frame 1 which is preferably hollow, as is clearly shown in Figure 2. It is obvious that a solid frame would be just as effective, without departing from the spirit and scope of my invention. The frame has a transverse hollow bar 2 which extends there-across. Glass supporting members 3 are carried by the bar 2 and support glass pieces 4. The members 3 extend inwardly beyond the

bar 2 and terminate flush with the inner surface of the glass 4.

A front plate 5 preferably of cardboard or other like material is disposed behind the glass 4, and is provided with an opening 6 therein (see Figure 1). A back plate 7 of wood is removably secured to the frame 1. The plate 7 has pegs 8 which project into openings in the frame 1, and has arms 9 which are adapted to be swung into slots 10 in the frame 1, whereby the plate is rigidly locked in place. The plate 7 carries a stub shaft 11 which extends through the bar 2 and projects therebeyond. As clearly shown in Figure 2, the shaft 11 is rigidly held in place by discs 12 and a pin 13. The shaft 11 has three discs 14, 15, and 16 rotatably mounted thereon.

The disc 16 is rigidly secured to a sleeve 17 by means of a pin 18, the sleeve being rotatably disposed on the shaft 11. In like manner the discs 14 and 15 are rigidly secured to sleeves 19 and 20 by pins 21 and 22. The sleeve 20 is rotatably mounted on the sleeve 17, while the sleeve 19 is rotatably mounted on the sleeve 20. It will further be noted from Figure 2 that the sleeves 17, 19 and 20 have flanges which space the discs 14, 15 and 16 slightly from each other and which also act as the supporting bases for the pins 21, 22 and 18 respectively.

Each of the sleeves 17, 19 and 20 extend through the bar 2 and are stepped with respect to each other. The sleeves are provided with actuating knobs whereby the discs may be rotated exteriorly of the frame. The knobs 23, 24 and 25 are disposed over the sleeves 17, 19 and 20 respectively, and have projections 26, 27 and 28 which extend into slots 29, 30 and 31 in the sleeves. The outer knob 26 is held in place by a washer and screw. From this construction it will be apparent that any one of the discs 14, 15 and 16 may be actuated.

The disc 14 is divided into twelve segments 32, each of these segments having a year imprinted thereon. In Figure 1, I have shown the segment 32 having the year "1922" imprinted thereon, in registration with the opening 6. The disc 15 in like manner is divided into twelve segments 33, these segments having the names of the months and the number of days in each month imprinted thereon. As will be clearly seen from the drawings, the month of "April, 30 Days" is in registration with the

opening 6, and may be readily viewed therethrough. The disc 16, however, is divided into seven segments 34, these segments having a calendar month thereon. It will further be noted that the calendars 34 have a number enclosed in a circle imprinted thereon, for a purpose hereinafter described. Each of the calendars 34 has the first day of the month fall on a different day. In the drawings I have shown the month which is used with the month of April in the year 1922. It will be noted that this calendar month 34 has a "6" imprinted thereon and has the first day of the month fall on Saturday.

It should be noted that all of the calendars 34 have 31 days therein. It is obvious, however, that certain of the months have a less number of days therein, as for example, the month of April, which is illustrated in the drawing. I dispose a slide 35, of the shape shown in Figure 1, directly in front of the disc 16, this card being movable so as to cover any portion of the last two rows of numbers in the calendar 34. A filler plate 36 has a cut away portion 37 which receives the disc 16. The filler spaces the slide 35 from the plate 7, so that the slide abuts the surface of the disc 16. A second filler plate 38 is disposed upon the filler 36 and is cut away at 39 to permit the free movement of the slide 35. In case the month of April 1922 were to be used, the slide 35 would be moved from the position shown in Figure 1, into a position in which the number 31 on the calendar 34 would be covered. The extended portion 40 of the slide is for the purpose of concealing some of the numbers on the fifth row of the calendar, as for example, when the month of February is used, which has only 28 or 29 days.

To ascertain which calendar 34 is to be used with a certain month and year, I provide two slides 41 and 42 which have the desired information thereon. These slides are mounted just behind the front plate 5 and at the lower corners of the device as illustrated in Figure 1. The plate 5 has rectangular openings 43 and circular openings 44 therein. The slides 41 and 42 have year numbers which are adapted to be registered with the openings 43, and other numbers from 1 to 7 which are adapted to be registered with the openings 44. The slides 35, 41 and 42 can be moved by means of guides 45 which are clamped to the slides and have trunnions which project through slots 46 in the sides of the frame 1 (see Figure 2). Certain of the guides are provided with knobs 47 by means of which the slides are moved. The slide 42 is spaced from the slide 35 by a filler 48.

From the foregoing description of the various parts of the device, the operation thereof may be readily understood. It will be

noted from Figures 1 and 4 that the discs 14, 15 and 16 are positively held against rotation by spring pressed pins 48, 49 and 50, the points of the pins being received in openings in the discs.

Assume that the month of April for the year 1922 is desired. The pin 48 is manually removed from the disc 14, thus permitting the latter to be rotated until the year 1922 is brought into registration with the opening 6. It will be noted that the discs 15 and 16 are held against rotation by the pins 49 and 50, when the disc 14 is rotated. The pin 48 is released when the number 1922 is brought into registration with the opening 6, and drops into one of the openings 51, thus preventing further rotation of the discs 14 until it is again manually moved outwardly. In like manner the pins 49 and 50 are manually removed from one of the rows of openings 51 and 52 respectively, thus permitting the discs 15 and 16 to be rotated. By rotating the disc 15, the month April is brought into registration with the opening 6. The slides 41 and 42 are moved by means of the guide handles 45 until the numbers 1922 of both slides are in registration with the openings 43. The number in the circular opening 44 which is disposed beneath the month "April" is the number of the calendar 34 to be used for this month. The number in the opening 44 under the word "April" is "6". The disc 16 is now rotated until the calendar 34, having "6" thereon, is brought into registration with the opening 6. Since there are only 30 days in the month of April, the slide 35 is moved until it covers the number 31 on the exposed calendar 34. The calendar is now ready for use for the current month. The numbers in the openings 44 designate the required calendars 34 to be used for the various months in a single year.

It is obvious that if the current month is in the last half of the year, the slide 41 can be moved to the next year. By merely replenishing the slides 41 and 42, the device can be used for an indefinite period.

The portion of the plate 5 which is disposed above the bar 2 can have a picture 53 or an advertisement disposed thereon. Information, such as general holidays, or the like, may be printed on the plate 5 below the openings 43 and 44. The device is efficient for the purpose intended and makes a pleasing appearance to the eye. The edges of the frame 1 are recessed so as to receive the guides 45. With this construction, the guides are hid from view, when the calendar is viewed from the front.

I claim:

1. A device of the type described, comprising a frame, a plurality of concentrically mounted discs having calendar information thereon, a plate disposed in front

of said discs and having an opening therein through which a portion of each disc may be viewed, and means projecting through the front of said casing for actuating said discs.

2. A device of the type described, comprising a frame, a plurality of concentrically mounted discs having calendar information thereon, a plate disposed in front of said discs and having an opening therein through which a portion of each disc may be viewed, means projecting through the front of said casing for actuating said discs, and spring pressed pins for positively locking said discs against rotation, said pins adapted to be manually released from said discs.
- 10 3. A device of the type described, comprising a frame, said frame having an opening in the front thereof, a plurality of concentrically mounted discs having portions thereof in registration with the opening, means extending in front of said frame for actuating said discs, manually controlled

- 20 means for positively preventing the rotation of said discs, said discs having calendar information thereon adapted to be brought into registration with said opening.
- 25 4. A device of the type described, comprising a frame, three concentrically mounted discs carried by said frame, one disc having year numbers imprinted thereon, the second disc having names of the months

imprinted thereon, and the third disc having seven calendar months imprinted thereon, each calendar month having its first day start on a different week day, a plate disposed in front of said discs and having an opening therein, means extending through the front of said frame for selectively rotating said discs to bring various portions thereof into registration with the opening, and means for ascertaining the required calendar month to be brought into registration with said opening when the year and month are known.

5. A device of the type described, comprising a frame, three concentrically mounted discs carried by said frame, one disc having year numbers imprinted thereon, the second disc having names of the months imprinted thereon, and the third disc having seven calendar months imprinted thereon, each calendar month having its first day start on a different week day, a plate disposed in front of said discs and having an opening therein, means extending through the front of said frame for selectively rotating said discs to bring various portions thereof into registration with the opening, means for ascertaining the required calendar month to be brought into registration with said opening when the year and month are known, and means for covering a portion of the exposed calendar month.

WILLIAM H. BAKER.
